UNITED STATES PATENT OFFICE

WILLIAM R. FRAMPTON, OF GLENDALE, CALIFORNIA, ASSIGNOR TO WESTINGHOUSE ELECTRIC & MANUFACTURING COMPANY, A CORPORATION OF PENNSYLVANIA

SERVICE SWITCH

Application filed April 14, 1920. Serial No. 373,919.

My invention relates to systems of electrical distribution. In such systems it is common practice to provide on the customers' premises an open service switch. The more progressive distributing companies now wish to use service switches which are entirely enclosed within metal boxes and each of which is preferably interlocked with the cover of its box so that the cover can only be opened when the switch is open. Such enclosed service switches while of great value from the standpoint of protecting the users and others against accidental contact with live parts of the switch, are objectionable from the point of maintenance in that it is very difficult to make tests of the meter or do any other work requiring auxiliary connections to the switch due to the difficulty and danger of making such auxiliary connections inside the box to live terminals therein.

Where the cover can only be opened when the switch is open, it is necessary to open the customer's circuit before access can be had to the switch which is also highly objectionable for many reasons. For these reasons many of the larger power companies have hesitated or refused to adopt an enclosed service switch.

It is an object of my invention to provide means whereby such a metal box may be provided with special facilities for making connections to the switch for testing purposes without opening the switch or interrupting the service and without the inspector handling live metal.

It is a further object of the invention to provide means for arranging these auxiliary connections so that they can be readily attached to any of the standard types of enclosed boxes now in use or which can be embodied in certain special forms of box to be hereinafter described.

It is essential that the auxiliary connections be guarded so that they can only be used by an authorized person and it is a further object of my invention to provide means for shielding or guarding these connections.

Referring to the drawing which is for illustrative purposes only, Fig. 1 is a view of

a certain type of switch box in which my invention is embodied, this box being shown in section to better illustrate the internal structure.

Fig. 2 is a side view of same.

Fig. 3 is an elevation partly in section of a similar type of box with the auxiliary connections arranged in a somewhat different manner.

Fig. 4 is a side view of same.

Figs. 5, 6 and 7 show different arrangements of the auxiliary connections as used in combination with a standard switch box as will hereinafter be explained.

Fig. 8 is a view on an enlarged scale showing the type of plug used by the meter tester, in connection with any of the boxes shown.

In the form of the invention shown in Fig. 1, a knife switch is shown, this switch being mounted on an insulating base 10, and consisting of upper jaws 11, lower jaws 12 and blades 13 which are pivoted in the jaws 12 and move in and out of the jaws 11. Fuse clips 14 carry enclosed fuses 15. Service wires 16 are connected with the jaws 11, and wires 17 leading to the customer's load are connected to the fuse clips 14. The blades 13 are operated thru an insulated bar 20 thru a crank 21 pivoted in bearings 22 and 23. This crank 21 is operated by a handle 24 which is outside of the box. A cover 25 is pivoted at 26 to the box 27 opening outwardly to give access to the interior thereto but being locked by mechanism 28 which is old in the art and need not be described.

The mechanism 28 is so constructed that the cover can only be opened when the switch is open, being securely locked in the closed position when the switch is closed. If it is desired to make any connection to the switch in its standard form of construction, it is therefore evident that the switch must first be opened to allow the cover to be opened to give access to the interior thereto. It is thus necessary for the meter tester to entirely interrupt the customer's load to get into the box.

For the purpose of allowing the inspector to make connection to the switch without opening the cover, I provide a series of

composition members 30 which are secured in the sides of the box 27 by nuts 31 and which carry conducting sockets 32. These sockets 32 are thus insulated from the box and are each connected by a wire 33 with one of the jaws 11 or 12. The sockets 32 are so constructed that a split or tapered plug 40 shown in Fig. 8 can be inserted therein from outside the box, an insulating handle 41 being provided for purposes of manipulation and a flexible wire 42 connected to the plug 40 being provided for the purpose of connecting the plug 40 to any kind of measuring or testing apparatus.

For the purpose of preventing unauthorized connections being made to the sockets 32 shields 50 are provided, these shields being hinged at 51 and being adapted to be sealed by any convenient means as shown at 52. It is possible after removing the seal 52 to turn the shield 50 back and allow plugs 40 to be inserted in the sockets 32. It is thus easy to put suitable jumpers around the switch or to divert the current which ordinarily passes thru the switch thru suitable testing apparatus by first making the proper connections and thereafter opening the switch.

In some cases the form shown in Fig. 2 is not convenient due to the fact that the switch box 27 is set into the wall so that the sides thereof are not accessible. In such cases the method of construction shown in Figs. 3 and 4 may be employed in which 60 is an auxiliary box provided with a shield 61 adapted to be sealed at 62, this auxiliary box 60 being secured to the side of a standard switch box 63. Wires 64 pass thru holes in the side of the box 63 connecting with the switch jaws inside the box and connecting to sockets 65 similar to the sockets 32. A box of this type may be set back into the wall and the meter tester can readily connect into the circuit by removing the seal 62, raising the shield 61 and inserting the plugs 40 in any manner desired.

In some cases I find it desirable to furnish standard attachments as shown in Fig. 5, these attachments each comprising an auxiliary box 70 secured by angles 71 to the side of a standard box 72. In some cases the method of construction shown in Fig. 6 may be employed in which an auxiliary box 80 is secured by rivets or bolts 81 to a standard box 82. In any case sockets 83 are employed, these sockets being connected thru wires 84 with the switch jaws. In some cases the sockets 90 may be secured in the cover 91 of a box 93 as shown in Fig. 7, sockets 90 being connected thru flexible wires not shown with the jaws of the switch inside the box. It is to be understood that where the form of constructions shown in Figs. 5, 6 and 7 is employed, that a suitable shield not shown is also employed, this

shield being sealed to prevent unauthorized persons from making connections.

I claim as my invention:

1. An enclosed switch comprising a casing, a cover for the casing, a current-controlling device within the casing having a meter test terminal member, an insulating bushing mounted on the casing and extending exteriorly thereof, and a socket for receiving a detachable test terminal mounted in the bushing and accessible from the exterior of the casing and connected to the said terminal member.

2. Current-controlling mechanism comprising a casing, a current-controlling device within the casing and having a meter test terminal member, a receptacle for receiving a detachable test terminal and connected to the said member and mounted on a wall of the casing and being accessible for reception of the said detachable test terminal only from the exterior of the casing, and a sealed cover for the receptacle.

In testimony whereof, I have hereunto set my hand at Los Angeles, California, on this 31st day of March 1930.

WILLIAM R. FRAMPTON.
